WALL WASHING APPARATUS

Filed Aug. 14, 1936

UNITED STATES PATENT OFFICE

2,233,632

WALL WASHING APPARATUS

Gunnar Moberg, Chicago, Ill., assignor, by mesne assignments, to Junius F. Cook, Jr., Hinsdale, Ill., as trustee

Application August 14, 1936, Serial No. 95,953

1 Claim. (Cl. 15—127)

My present invention relates in general to the control of fluid under pressure and more particularly to means for and method of applying liquids on surfaces to be treated, the invention, more specifically, relating to fluid pressure apparatus for the application of liquids on surfaces to be cleaned.

An important object of the invention is to provide pressure storage apparatus and means for delivering liquid at all times under the control of an operator situated remotely from the storage apparatus, a further object being to deliver the liquid for uniform application on a surface to be treated with said liquid.

Another important object is to provide an improved applicator for applying liquid, delivered under pressure to said applicator, substantially uniformly and in regulated quantities, upon a surface to be treated with said liquid; a further object being to arrange the applicator in the form of a trowel comprising a preferably flat, perforated plate, and a handle attached on the back of said plate and providing a liquid delivery chamber on one side of the plate and communicating with the plate perforations, said handle having a valve conveniently mounted to facilitate operation thereof by a person grasping said handle whereby to afford instant control of liquid flow, under pressure, to said chamber so that regulation of liquid pressure in said chamber and hence of the flow of liquid from the chamber through the plate perforations may at all times be had under the control of a person manipulating the applicator.

Another important object is to provide simplified means for detachably securing a pad, such as a towel, cloth or other porous fabric, upon the face of the trowel in position to receive liquid delivered through the openings of the trowel plate, whereby the pad may become saturated and serve to spread the liquid uniformly on a surface to be treated.

Another important object is to form the applicator in such a way as to reduce the cost of manufacturing and assembling the same, including the formation of the handle as a casting requiring a minimum amount of drilling and finishing operations, and providing a chamber into which liquid under pressure may be introduced, under the control of a valve, in position to escape thence through openings in the face of the trowel to maintain in uniformly saturated condition a liquid spreading pad attached on said face.

Another important object is to provide simpli-

fied clips for securing the liquid spreading pad upon the perforated face of the trowel plate; a further object being to mount the clips upon the handle portion of the trowel in position to bear resiliently upon the back of the trowel plate near the edges thereof.

Another important object resides in the simplified valve structure and the arrangement thereof in the handle portion of the trowel whereby standardized commercial fittings may be utilized in the assembly.

Among the other important objects of the present invention is to fabricate the trowel principally of aluminum in order to reduce its weight, thereby reducing the effort required to manipulate the same in applying liquids, especially on wall and ceiling surfaces; to provide wall washing equipment which is essentially portable, is of simplified construction, easy to operate, and adapted for manufacture at low cost; to provide fluid pressure equipment for the delivery of liquids at operating pressure at a remote station for application on a surface to be treated, including means, under the control of the operator at the point of application, for regulating the flow of the liquid to the end that it may be applied uniformly and at a desired rate on the surface being treated; and, in general, to improve wall washing facilities, to reduce the cost of washing operations, and to provide means whereby the same may be carried on with maximum efficiency.

These and numerous other important objects, advantages and inherent functions of the invention will become apparent as the same is more fully understood from the following description, which, taken in connection with the accompanying drawing, discloses a preferred embodiment of the invention.

Referring to the drawing:

Figure 1 is a perspective view of fluid pressure apparatus embodying my present invention; and

Figures 2, 3, 4, 5 and 6 are sectional views taken substantially and respectively along the lines 2—2, 3—3, 4—4, 5—5 and 6—6 in Figure 1.

To illustrate my invention, I have shown, on the drawing, fluid pressure apparatus comprising tank means 11 adapted for the storage of liquid under pressure, a broad feature and purpose of my invention being to provide for storing liquids, under pressure, preferably in separated fashion in the tank means whereby the liquids may readily be delivered, selectively or otherwise, from the tank means. To this end the tank means may provide a plurality of stor-

40

55

age chambers and means 13 is provided for delivering the stored liquid, at a point remote from the container 11 for application as in the washing of wall and like surfaces.

5 The washing of wall surfaces usually requires the application of at least a cleaning fluid and a rinsing fluid in succession on the surfaces to be cleaned, and I therefore provide means, such as a partition, within the container 11 defining a 10 plurality of storage chambers, the partition being preferably secured in the container 11 in any suitable fashion preferably preventing liquid leakage between the chambers.

15 The partition, however, is arranged to afford communication between the chambers, preferably at the upper end of the container 11, as through an opening at the top of the partition near the top 25 of the container. The top 25 of the container may be formed with openings affording access to each of the compartments so 20 that said compartments may be charged or loaded each with a liquid different from that contained in the other. The loading openings are preferably provided with standard fittings 29 sealed in said openings and externally threaded 25 to receive cover elements 31 by means of which the openings may be sealed, said cover elements being readily removable by unscrewing the same from the threaded fittings 29, in order to permit liquids to be introduced into the compartments.

30 One of the covers 31 may carry a gauge 33 for indicating the pressure within container 11. Another cover 31, preferably carries a pump having an operating handle 47, by means of which desired pressure conditions may be established within the container 11 including the compartments thereof so that the liquid in each compartment may be placed under like pressure by operation of the pump means 47.

40 By removing the caps 31, one of the compartments may be filled with a soap solution or other cleaning fluid, and the other compartment may be charged with a rinsing liquid such as water. The covers 31 may then be replaced and, by 45 operating the pump 47, a suitable operating pressure may be developed within both compartments, the pressure so developed being indicated on the pressure gauge 33. In order to retain the pressure so developed it is desirable to provide resilient sealing rings within the covers 31 in position to be compressed by and between the covers 31 and the ends of the fittings 29 on which said covers are threadedly secured. A similar gasket may also be applied and compressed by 55 and between the cover and the end of the pump barrel.

50 The liquid applying means 13 comprise trowels or applicators operable to deliver liquid, substantially uniformly from the container 11 and at a rate controlled by the operator of the trowels, for application on a surface to be treated with the liquids. Where liquids of different character are applied, I prefer to provide a trowel for each different kind of liquid, each trowel being connected with one of the liquid compartments, preferably by means of a flexible conduit 53.

55 The trowels or applicators 13 may be of any suitable or preferred form, but I prefer to utilize applicators of the character and form shown in the drawing. The illustrated applicators comprise each a plate portion 55, and a handle bracket 57, the plate portion comprising a preferably rectangular element formed with a row of spaced perforations 59, preferably arranged along 70 the medial line of the plate. The handle bracket

75 preferably comprises a casting having a substantially flat surface in position to overlie the perforations 59 on the back of the plate 55, a gasket 61 being applied between the casting and the back of the plate 55 to define a closed chamber 62 in communication with the perforations 59. The bracket is also formed with a pair of spaced handle carrying uprights 63, one of which is formed with a preferably integral perforated lug 64, extending outwardly thereof in a direction 10 away from the other upright and in a plane substantially parallel with the bottom surface of the bracket on which the plate 55 is mounted. A handle 65 is mounted in position extending between the upper ends of the uprights 63, said 15 handle preferably being carried on a pin 67, the opposite ends of which are secured as at 69 to the uprights 63. The body of the bracket 57 also is formed with a channel 71, extending preferably from end to end of the bracket, which channel may be formed by drilling or coring the casting. The opposed ends of the channel are closed, 20 preferably by means of plugs 73 threaded in the ends of the channel, and sealed in place as with shellac to prevent leakage.

25 The bracket 57 is formed with a threaded opening adapted to receive one end of an elbow 75, said elbow connecting with said channel 71 at or near one end of the bracket. The other end of the elbow is threaded to receive a gland 30 77, by means of which a preferably copper tube 79 is secured to the elbow, suitable packing 81 being held in place by the gland 77 to prevent fluid leakage at this point. A flexible, preferably rubber, tube forming the conduit 53 is attached 35 on the projecting end of the tube 79, the other end of the conduit 53 being connected on a similar, preferably copper, tube 83, which is or may be secured, by means of a gland 85, in a tubular fitting 87, which, in turn, is or may be 40 threaded in an embossment 89 formed in the wall of the container 11 and communicating with one of the chambers thereof.

45 Liquid under pressure may thus be delivered through the conduit 53, into the channel 71 of the trowel at substantially the pressure prevailing within the container 11. The channel 71 also is connected with the chamber 62 through a valve mechanism 91 mounted in the bracket 57. The bracket 57 is formed with an embossment 50 93 adjacent one of the uprights 63 and preferably adjacent the end of the bracket opposite from that at which the elbow 75 is attached. The embossment 93 receives a fitting 95 forming 55 a valve chamber having an opening 97, communicating at one end with the channel 71, the end of the fitting 95 forming a valve seat adapted to receive a valve disk 99 in position to open into the channel 71, so that the valve is normally urged toward closed position by the pressure of 60 liquid delivered in the channel 71 from the container 11. The valve chamber 95 is connected, by means of a conduit 101, with the cavity 62, so that when the valve 99 is shifted to uncover the opening 97, liquid may pass, from the channel 65 71, through the valve chamber 95 and the conduit 101, and enter the cavity 62 in position to flow thence through the openings 59, and thus be delivered, at a rate at all times under the control of the valve, in position to be applied 70 upon a surface to be treated.

75 The valve disk 99 is carried upon a valve stem 103, which extends through the fitting 95 and the valve chamber defined therein, and thence through the opening on the flange 64, the stem 75

103 terminating in a button 105 in position opposite the end of the handle 65, so that the button and stem may be readily pressed by a person holding the handle whereby valve movement is 5 at all times under thumb control.

The valve stem 103 is normally urged, in a direction to close the valve 99, by means of a spring 107 seating, at one end, in a socket formed in the flange 64, and, at the other end, upon the button 105. The valve chamber 95 has a normally open top which is sealed, around the valve stem 103, by suitable gland means 111, preferably threadedly interfitted on the upper end of the valve chamber 95 in order to compress a 10 suitable packing material 113 around the valve stem and prevent fluid leakage from the valve chamber at this point.

The plate 55, of course, may be secured in place upon the bracket 57 in any suitable fashion, although I prefer to employ screws 115 penetrating the plate and the gasket 61 and taking into the body of the bracket 57. I also prefer to form the bracket as an aluminum casting and to utilize aluminum or similar relatively light 25 weight material in the plate 55, in order thus to reduce the total weight of the trowels to the lowest possible minimum, to the end that persons using the washing apparatus may not become unduly fatigued through continuously holding 30 and swinging the trowels, especially in performing overhead washing operation.

Washing in accordance with my present invention is accomplished by controlling the flow of liquid to the chamber 62 and through the 35 openings 59 at a rate sufficient to maintain a liquid spreading pad 117, on the face of the plate 55, in a desired moist or saturated condition, the apparatus of my present invention being operable to regulate the flow of liquid to the pad 117 substantially exactly at a rate necessary to maintain the spreading pad in properly saturated 40 condition whereby the liquid may be applied uniformly on the surface being treated, and at a rate best suited to efficient washing, the application 45 of liquid being such that wastage of the liquid is reduced to a minimum.

I also provide simplified means 119 for securing the spreading pad in readily demountable fashion on the face of the plate 55, the means 50 119 comprising preferably four clips 121, formed of sheet metal and mounted in pairs at the opposite ends of resilient spring elements 123. The mid-portions of the springs 123 are secured in seats 125 formed in the bracket 57, the springs being 55 secured in place in any suitable fashion preferably by means of the holding screws 127. The springs 123 extend outwardly on opposite sides of the bracket and support the clip elements 121 adjacent the opposite side edges of the plate 55.

60 The clips 121 preferably have saw-tooth edges 129 normally urged by the resilience of the springs 123 toward the back of the plate 55 in position to engage the opposite edges of the pad 117. The clips 121 also are preferably formed 65 with offset lugs 131, which may be riveted to the springs means 123, as shown at 133, in order to secure the clips on the springs. The clips also have upstanding ears 135, by means of which they may be raised from the plate 55 in order to 70 permit insertion or removal of the pad 117.

Where the surface being treated is of irregular character, I provide a layer of yielding material, such as sponge rubber, between the towel 117 and the face of the plate 55. This layer may 75 have clips to secure it to the plate, as at the

corners thereof. This layer serves to permit the pad 117 to follow the irregularities of the surface.

It will be apparent from the foregoing that the washing of walls, ceilings and the like, and in fact the application of fluid on any surface will be greatly facilitated and may be accomplished at maximum efficiency as to time and materials consumed by the use of the apparatus of my present invention, since said apparatus affords means whereby liquid is instantaneously available, in regulated quantities and without any waste, at the place where it is desired to apply the liquid on the surface being treated. The apparatus, moreover, permits washing operations to take place continuously and without interruption or loss of time for rinsing or dipping for additional fluid as is the case where usual methods and equipment are employed. The container 11 is preferably supplied with a suitable supporting base 137, which may be provided with casters for mobility, if desired, and the top 25 of the container may be provided with a suitable carrying handle 139, so that the apparatus is entirely portable and may be readily carried from place to place. Convenient hooks 141 may also be provided for hanging the trowels on the container when not in use. The conduits 53, during idle periods, may be wrapped around the container whereby the entire apparatus, when not in use, presents a neat, compact appearance and is adapted for storage in minimum space.

For wall washing purposes I prefer to supply an additional trowel for drying purposes. This additional trowel, however, need have no provision for the valved delivery of liquid to and through the plate, and may simply comprise a plate having a handle and clip means for securing a dry, absorptive pad upon the face of the plate in a manner heretofore described in connection with the wet trowels 13.

The washing process then comprises the application of a cleaning solution by means of one of the trowels 13, followed shortly by the application of a rinsing solution by another of the trowels 13, and a final drying accomplished by means of the additional dry trowel, heretofore mentioned. It is obvious, however, that the apparatus of my present invention may be utilized for other purposes than that of washing and I do not necessarily wish to limit the invention specifically for use in washing operations. It will be noted, however, that the apparatus is of extremely simple construction and may be built largely of standardized commercial fittings, so that the entire apparatus may be made at low cost. The apparatus, however, is unusually simple, easy and convenient to operate and at the same time furnishes means whereby wall washing operations may be carried on continuously with a minimum of effort and at high efficiency, thereby substantially reducing the cost of such operations.

It is thought that the invention and its numerous attendant advantages will be understood from the foregoing description; and it is obvious that numerous changes may be made in the form, construction and arrangement of the several parts without departing from the spirit and scope of the invention or sacrificing its attendant advantages, the form herein described being a preferred embodiment for the purpose of demonstrating the invention.

Having thus described my invention, what I

claim is new and desire to secure by United States Letters Patent is:

In washing apparatus, a liquid applicator comprising a plate-like blade and a blade mount comprising a seat, spaced uprights forming a handle support, handle means extending between said spaced uprights, and means to secure the plate on said seat to form a liquid delivery chamber therebetween, said blade being formed with 5 perforations therethrough connecting with said delivery chamber and opening on a surface of said blade remote from said chamber, said blade mount being formed with an embossment at the base of one of said uprights and having an inlet 10 compartment formed for connection with an external source of liquid under pressure, said embossment having a valve receptacle cavity connected at one end with said inlet compartment, a member forming a valve seat removably se-

cured in said receptacle cavity and forming a valve stem guide, a duct extending in the embossment and communicating with the receptacle cavity therein on the side of the valve seat remote from said inlet compartment, and a passage in said embossment substantially parallel with respect to said receptacle cavity and connecting said duct with said delivery chamber, and a valve stem supported in said guide in position extending adjacent one of said spaced uprights, a valve member at one end of said stem in position to engage the valve seat between the inlet compartment and said duct, said stem terminating at its other end adjacent an end of said handle means, and spring means normally 15 urging said stem in a direction to press the valve member on said seat.

GUNNAR MOBERG.
